JOHN P. WEIS, OF BROOKLYN, NEW YORK, ASSIGNOR, BY MESNE ASSIGNMENTS, TO METROPOLITAN SEWING MACHINE COMPANY, A CORPORATION OF NEW YORK.

TRIMMING MECHANISM FOR SEWING-MACHINES.

1,155,533.

Specification of Letters Patent.

Patented Oct. 5, 1915.

Application filed June 5, 1903. Serial No. 160,203.

To all whom it may concern:

Be it known that I, JOHN P. WEIS, a citizen of the United States, residing in Brooklyn, county of Kings and State of New York, have invented a new and useful Improvement in Trimming Mechanism for Sewing-Machines, of which the following is a description.

This invention relates to trimming mechanism for sewing machines, and particularly to a trimming mechanism which can be applied to any sewing machine.

An object of my invention is to provide a trimming mechanism which will be positive in its action and trim the work with ease.

Another object of my invention is to provide a trimming mechanism which can be readily applied to any sewing machine, without altering any of the parts of the latter; which may be removed from the machine with facility; and thrown out of action when not required.

Other objects of the invention will appear during the course of this description.

The invention consists in the parts, elements and combinations hereinafter described and claimed.

In the drawings: Figure 1 is a perspective view of so much of a sewing machine as is deemed necessary to illustrate the application of the trimming mechanism, and showing the trimming mechanism applied to the machine, the cloth-plate of the machine being shown in dotted outline merely; Fig. 2 is a top plan view of a portion of the trimming mechanism; Fig. 3 is a side elevation of the parts shown in Fig. 2; Fig. 4 is a front elevation of the parts shown in Fig. 3; Fig. 5 is a vertical section on the line 5—5 of Fig. 2, of the pivotal support for the trimmer-lever; Fig. 6 shows, in side elevation, the two portions of the supporting bracket, the same being arranged in juxtaposition so as to portray the manner of assembling the same and the co-operation of the several features thereof; Fig. 7 is a plan of the trimming mechanism, showing the actuating parts disconnected and the trimmer-blade in an inoperative position; and Fig. 8 is a side elevation of the parts shown in Fig. 7.

The bed-plate of the machine is indicated by 1, the cloth-plate in dotted outline by 1^a, in Figs. 1 and 8, the driving-shaft by 2, the

feed-dog by 3, the latter being carried by the bar 4, fixed at its rear end to the shaft 5, journaled in the rocking-frame 6, journaled by the shaft 7, in brackets 8, on the bed-plate. The rocking-frame 6, derives its motion from the forward end of the shaft 2, through the medium of the usual connection 9; and the vertical movements of the feed-bar are given by the usual eccentric located near the forward end of the main-shaft and embraced by the said bar and its hanger 10. The needle is indicated by 11, and the presser-bar by 12.

The trimmer mechanism includes the bracket, consisting of the main vertical portion 13, having at its bottom the horizontal portion 14, the main portion having the horizontal groove 13^a extending across its back for receiving the edge of the bed-plate, as shown in Fig. 8. The portion 14 is secured to the bottom of the bed-plate 1, by means of screws passing through the apertures 15. The horizontal portion 14 of the bracket and its groove 13^a constitute a means which, under slight modification, enable the bracket 13 to be adapted, or fitted, detachably, to the bed-plate of practically any sewing machine, so that the main portion of the bracket will extend vertically in position, at the front of the machine, to support the detachable portions of the trimming mechanism and enable them to be removed from the machine, in their entirety, at the will of the operator, quickly and without disturbing any of the other mechanisms of the machine. The face of the bracket 13, is provided with a holding and adjusting plate 16, provided with an elongated slot 17, through which passes a screw 18, to hold the same rigidly but adjustably to the face of the bracket 13. The removable bracket 19, is made angular as shown in Fig. 6, and its vertical portion is provided with the inclined face 20, notch 21, and depending portion 22, the latter being embraced by the extension 23 at opposite ends of the plate 16, the upper edge of said plate resting in the notch 21, and the bracket 19, being thus supported between the holding plate and the bracket 13. In this position the removable bracket 19, is rigidly held in place by means of the latch-lever 24, secured by means of the screw 25, to the vertical portion of the bracket 13, said lever being provided with a handle 26, and a notch 27, and a finger 28. A pin 29,

on the bracket 19, is engaged by the finger 28, and received by the notch 27, of the lever 24, the latter thus holding the two brackets firmly together. A spring washer 30, is held between the head of the screw 25, and the lever 24, in order that the latter may have sufficient friction applied thereto to prevent the same from being accidentally thrown out of place and also for holding 10 said latch in any position to which it may be moved. The upper inclined portion of the bracket 19, is split at 31, to provide a clamp for the purpose of holding an adjustable bushing 32, in proper position. The 15 said bushing is clamped by means of the screw 33, tapped into the bracket at the split portion. The bushing 32, is provided with a knurled head for manipulating the same.

Passing through the bushing 32, is a shaft 20 34, having the head 35, at one end adjacent the head of the bushing 32. The other end of the shaft is supported by bushing 34, held in one of the extensions 38, of bracket 19; and said shaft is bored longitudinally 25 for the reception of oil or other lubricant. The said shaft is also provided with transverse apertures 36, through which the oil may pass to the journal supports or bearings; and the ends of the shaft are suitably 30 plugged as shown at 37, to prevent the escape of the lubricant. The shaft oscillates in the bracket 19, and has fixed thereto, between the extensions 38, of said bracket, the sleeve 39, of the trimmer-lever 40, which is 35 in the form of a bell-crank, the horizontal arm of which has secured thereto the trimmer-blade, by means of the set screw 42, passing through said arm and into or through the blade. Sleeve 39, has apertures 40 through which oil may be introduced to shaft 34. Said blade is provided with the shank 43, the elongated stem 44, and the overhanging portion 45. The edge of the portion 45, is beveled as shown in Fig. 1, at 45 46. Said blade co-operates with a blade 41, held in the arm 47, of the bracket 19. The blade is seated in a groove 48, in the bracket-arm 47, and is held therein, with its cutting-edge substantially flush with the surface of 50 the cloth-plate 1^a, Fig. 8, by means of the lever 49, pivoted at 50, to the arm 47, and provided with a cam end 51, which impinges upon the blade 41. The vertical arm of the bell-crank lever 40, is connected at its lower 55 end to the piston-socket 52, by means of the clamp collars 53. Substantially midway between its ends, the socket 52, has a collar 54, clamped theron, and pivoted to the top of said collar is a lever 55, having its forward 60 end provided with a hook 55', and its rear end provided with a manipulating handle 56. Adjacent the handle the lever is provided with a notch or groove into which extends a lug 57, which may be formed on the 65 pin 29, for locking the trimmer-blade out of

action. Rigidly secured to the collar 54, in proper position, is a coiled spring 59, the forward end of which engages the back of the lever 55.

The shaft 2, of the machine is provided 70 with the eccentric 60, surrounded by the strap 61, having the extension or piston 62, secured thereto and entering the longitudinal bore of the piston-socket 52. The said piston or an enlargement 63, thereof provided in any manner, is provided with a holding pin 64, which is engaged by the hook 55', of the lever 55. Thus a firm but detachable connection is made between the driving shaft of the machine and the trimmer mechanism, causing the eccentric on the driving shaft to actuate the trimmer lever 40, and move its blade vertically relatively to the stationary ledger-blade 41, thus securing the proper co-operation of the trimmer blades for the purpose of trimming the work. It will be obvious that the cutting edge 46, of the trimmer-blade is sufficiently elevated above the work lying upon the cloth-plate, to enable the latter to be passed under the same for the purpose of trimming the edges thereof. When the trimmer-blade is in action the piston-socket is held rigidly against the enlargement 63, of the piston by the spring-latch 55, the hook 55', of which engages the pin 64. When the trimmer blade is to be thrown into action, the handle 56, is pressed to release the same from the lug 57, and cause the hook 55' to assume a position to engage the pin 64. This may be done while the machine is in operation and without affecting the action thereof; and then the handle 56, is pressed quickly forward and released, when the spring will cause the hook 55', to engage the pin 64, and lock the piston and socket together. This action throws the trimmer-blade above the cloth-plate and the eccentric 60, becomes operative to actuate the trimming mechanism. The trimmer-blade is thrown out of action, while the machine is in operation, with equal facility, it being only necessary to slightly press the handle 56,—thus releasing the pin 64, from hook 55',—and then draw the same back to engage the same with the lug 57, allowing the piston to reciprocate in the socket 52, without effect. When the trimmer blade is depressed, its upper edge is substantially flush with the edge of blade 41. See Fig. 8. To render the connection between the sleeve 39, and the shaft 34, firmer, a pin 39', is passed through the sleeve and through the shaft, thus securely fixing the two together. Any lateral adjustment of the trimmer-blade relatively to the ledger-blade 41, may be secured by adjusting the bushing 32, the knurled head of which bears upon the head 35, of the shaft, and the other end of which bears upon one end of the sleeve 39. Suffi- 180

cient space between the opposite end of the sleeve and the adjacent bearing 38, is provided to enable the proper adjustment to be made. It will now be clear that by manipulating the bushing the trimmer-blade may be adjusted relatively to the ledger-blade, turning the bushing to the right causing its end to bear upon the sleeve and move the trimmer-blade toward the ledger-blade, and turning it to the left causing its head to bear upon the head of the shaft and move the trimmer-blade in the opposite direction. Vertical adjustments of the trimmer blade may be made by manipulating the clamping screw 42.

From the above description it will be seen that I have provided a simple trimming mechanism, which may be attached to any sewing machine, and actuated from the driving shaft of the latter by the mere application of an eccentric and strap, and which may be considered, from one aspect, as a trimming attachment applicable to any sewing machine having an eccentric and strap on an actuating shaft. It will further be seen that my trimmer mechanism eliminates all the parts which usually appear above the the cloth-plate of the machine, and leaves the latter entirely free for the support and manipulation of the work. It will also be seen that the parts of the trimmer mechanism are few, simple and strong, and that the bearings are few and easily lubricated. Further, that fine and nice adjustments can be made quickly and conveniently, and by simply manipulating a couple of the elements of the mechanism; and that the trimmer-blade can be thrown into and out of action quickly and easily.

Having thus described my invention what I claim and desire to secure by Letters Patent is:

1. In combination with the bed-plate of a sewing machine, a bracket, one portion of which engages the bottom and the other portion of which engages the edge of said bed-plate; means by which the bracket may be detachably secured to said bed-plate; a second bracket, and complementary means between the two brackets for coupling one detachably to the other; a trimming mechanism comprising a stationary and a vibratory blade carried by said second bracket; and means for actuating said vibratory blade.

2. In combination with the bed-plate of a sewing machine, a bracket one portion of which engages the bottom and the other portion of which engages the edge of said bed-plate; means by which the bracket may be detachably secured to said bed-plate; a second bracket, and complementary means between the two brackets for coupling one detachably to the other; a trimming mechanism comprising a stationary and a vibra-

tory blade carried by said second bracket; and means for actuating said vibratory blade including a detachable connection therefrom to the driving member of the actuating means.

3. A trimming mechanism comprising a bracket one portion of which has means adapting it to be secured to a supporting frame, and another portion of which has supporting means; a second bracket having means cooperating with the supporting means of the first named bracket for coupling the two brackets detachably together; trimming mechanism carried by the second bracket; and means for adjusting the two brackets relatively to each other.

4. In combination with the cloth-plate of a sewing machine, a trimming mechanism having a fixed blade and a movable blade, means for securing the trimming mechanism to the machine with the cutting edge of the movable blade below the surface of the cloth-plate, means for projecting the movable blade through the cloth-plate into operative position and maintaining it thus during its operation, and means whereby the movable blade may be actuated.

5. In combination with a sewing machine, a trimming mechanism having a fixed blade and a movable blade, means for detachably securing the movable blade and its actuating mechanism to the machine below the cloth-plate thereof so that the latter will shield the same, means for projecting the movable blade through the cloth-plate into operative position and for maintaining it thus during its operation, and means for actuating the movable blade.

6. In combination with a machine-frame, a trimming mechanism; means for detachably securing the trimming mechanism to the edge of the bed-plate at the front of the machine; means for actuating the trimming mechanism including a driving-shaft, and a detachable, positive driving connection between said shaft and the trimming mechanism; and means by which the latter may be thrown in and out of operation during the running of the machine without affecting the operation of said shaft, whereby the trimming mechanism may be stopped and removed from the machine.

7. In combination, a sewing machine; a trimming mechanism, carried by said machine, having a ledger-blade, said trimming mechanism also including a vibratory trimmer-blade capable of being moved through the machine cloth-plate to an operative position above the surface of the same; means connecting with the driving-shaft of the machine for actuating said trimmer-blade; and means whereby the trimmer-blade may be thrown into and out of action through the cloth-plate during the operation of the machine.

8. In combination, a sewing machine; a trimming attachment; means for detachably securing said attachment to the machine with all its functional parts except the cutting edge of the ledger-blade below the surface of the cloth-plate thereof; means on the driving-shaft of the machine for actuating the attachment; and a detachable connection between said actuating means and the attachment, whereby the trimmer-blade of the latter may be projected through the cloth-plate to be put in and out of operation during the operation of the machine.
- 10 9. In combination with a sewing machine, a bracket fixed thereto below the cloth-plate, a trimming mechanism comprising a ledger-blade and a trimmer-blade, a common support for the two blades, means for detachably connecting the support to the bracket, means for driving the trimmer-blade including a connection in separable parts located below the cloth-plate of the machine, and means whereby said parts may be separated during the running of the machine to put the trimmer-blade out of operation.
- 15 10. In combination with a sewing machine, a bracket fixed thereto below the cloth-plate; a trimming mechanism, comprising a ledger-blade and a trimmer-blade, supported on said bracket with all the functional parts except the cutting edge of the ledger-blade normally below the surface of the cloth-plate, said trimmer-blade having a pivoted carrier which moves said blade through the cloth-plate into operative position, and means for actuating the carrier including a detachable connection to the latter.
- 20 11. In combination, a sewing machine; a trimming mechanism, all the movable parts of which are carried by the machine below the cloth-plate thereof, including among its elements a device for supporting the trimming-blade thereof in position to perform its trimming function; actuating mechanism for said trimming mechanism including a driving-shaft and telescoping parts detachably connected together and also located below the said cloth-plate; and means for operatively coupling said parts so that they will have no relative movement and so that all the movements of said trimming mechanism will be positive.
- 25 12. A trimming mechanism comprising means for supporting a ledger-blade; means for supporting a trimmer-blade; means for actuating the trimmer-blade, including a driving-shaft and detachable telescoping parts one of which is carried by said shaft; and a spring latch for positively holding the two parts together.
- 30 13. A trimming mechanism having in combination a bracket; two coöoperating blades; means for supporting said blades on said bracket; and means for adjusting said blades relatively to each other, said means being carried by said bracket and including a shaft, and a bushing surrounding the shaft 70 and screw-threaded into said bracket.
- 35 14. In combination, a sewing machine; a fabric trimming mechanism, all the movable parts of which are supported by said machine below the cloth-plate thereof and comprising a stationary blade and a vibratory trimmer-blade; and means whereby the trimmer-blade of said mechanism may be moved through said cloth-plate to operative position above the same at will during the 80 operation of the machine.
- 40 15. In combination with a sewing machine, a trimming mechanism supported thereby below the cloth-plate and comprising a stationary blade and a vibratory trimmer-blade, means for actuating the trimming mechanism whereby its trimmer-blade only is moved through the cloth-plate, and means whereby the trimming mechanism may be thrown out of operation and its 90 trimmer-blade depressed with its cutting edge below the surface of the cloth-plate during the operation of the machine and without affecting the stitching of the latter.
- 45 16. In combination with a sewing machine, a trimming mechanism comprising a stationary blade and a reciprocating blade, said mechanism being attached to the machine below is cloth-plate, means for actuating the trimming mechanism to cause its reciprocating blade to operate freely through the cloth-plate, and means whereby the trimming mechanism may be thrown into and out of operation during the operation of the machine and without affecting the sewing of the latter.
- 50 17. A trimming mechanism comprising a ledger-blade and a trimmer-blade arranged in parallelism and normally below the cloth-plate, common means for supporting the blades in coöperative relation, and means for adjusting the trimmer-blade positively toward and from the ledger-blade and positively maintaining the adjustment.
- 55 18. A trimming mechanism comprising a ledger-blade and a coöoperating trimmer-blade, the latter having a notched portion to receive the work and an overhanging cutting edge, and mechanism for actuating the trimmer-blade including means for throwing the latter out of operation and for depressing the cutting edge thereof below the edge of the ledger-blade.
- 60 19. In combination with a sewing machine; a trimming mechanism attached thereto below the cloth-plate comprising a ledger-blade and a trimmer-blade; means for actuating the trimming mechanism whereby its trimmer-blade only is projected above the cloth-plate; and means whereby 130

the trimmer-blade may be thrown out of operation during the operation of the machine and its upper edge located substantially flush with the upper edge of the 5 ledger-blade.

20. In combination with a machine, a trimming mechanism having a fixed blade and a movable blade; means for supporting the movable blade normally at rest below the 10 work-plate of the machine; actuating mechanism for the movable blade; and means whereby said blade may be projected through the work-plate into operative position and simultaneously set in operation.

15. 21. A trimming mechanism including, in combination, trimmer-blades, an eccentric on the driving-shaft of the machine, a strap engaging eccentric, a telescopic connection between said eccentric and one of said 20 blades, means for holding the telescopic parts operatively together, and means whereby the parts of the telescopic connection may be detached during the operation of the trimming mechanism.

25. 22. In combination with a sewing machine, a trimming mechanism comprising a ledger-blade, a reciprocating trimmer-blade, and means for actuating said trimmer-blade, all the functional parts except the cutting edge of the ledger-blade being located 20 below the surface of the cloth-plate of the

machine; and means whereby the trimming blade may be thrown into and out of action during the operation of the machine and without affecting the usual functions of said 35 machine.

23. A trimming mechanism comprising a trimmer-frame, a ledger-blade and a trimmer-blade carried by said frame, a holding bracket, and means between the said frame 40 and bracket whereby the trimmer-frame may be accurately seated on the holding bracket and securely held in place on the latter.

24. A sewing machine including, in combination, a work support; a trimming mechanism comprising a ledger blade, and a cutting blade projecting above said work support and cooperating with said ledger blade; means for operating the cutting blade; and 45 means for raising the cutting blade above the work support and lowering said blade beneath the same during the operation of the machine, whereby its cutting action is rendered effective or ineffective.

In testimony whereof I have hereunto signed my name in the presence of two subscribing witnesses.

JOHN P. WEIS.
